Henry Dreyfuss, South Pasadena, Calif., and Lionel W. Mosing, Springfield, and Robert E. Prescott, Rumson, N.J., assignors to Bell Telephone Laboratories, Incorporated, New York, N.Y., a corporation of New York

Filed Sept. 21, 1964, Ser. No. 81,798

Term of patent 14 years

(Cl. D26—14)

FIG. 1

FIG. 5

FIG. 2

FIG. 3

FIG. 4

FIG. 6

FIG. 7

FIG. 8

FIG. 1 is a perspective view of a telephone handset, showing one form of our new design wherein the transmitter portion is faired into the body of the handset;

FIG. 2 is a top plan view of the form shown in FIG. 1, to an enlarged scale;

FIG. 3 is a side elevational view of the form shown in FIG. 1, to an enlarged scale, the opposite side being substantially a mirror image thereof; and

FIG. 4 is an end elevational view of the form shown in FIG. 1, to an enlarged scale;

FIG. 5 is a perspective view of a telephone handset, showing another form of our new design wherein the transmitter portion is stepped above the level of the inner face of the handset;

FIG. 6 is a top plan view of the form shown in FIG. 5, to an enlarged scale;

FIG. 7 is a side elevational view of the form shown in FIG. 5, to an enlarged scale, the opposite side being substantially a mirror thereof; and

FIG. 8 is an end elevational view of the form shown in FIG. 5, to an enlarged scale.

The dominant features of our design reside in the portion shown in solid lines on the drawing.

This application is a continuation-in-part of our pending application, Serial No. D. 72,400, filed November 6, 1962, now abandoned.

We claim:

The ornamental design for a telephone handset, substantially as shown and described.
